Dominick W. Sharkey
Inventor
By his Attorney
Williams & Pritchard

UNITED STATES PATENT OFFICE.

DOMINICK W. SHARKEY, OF SYRACUSE, NEW YORK.

AEROPLANE.

1,355,624.

Specification of Letters Patent.

Patented Oct. 12, 1920.

Original application filed November 27, 1917, Serial No. 204,156. Divided and this application filed December 24, 1918. Serial No. 268,148.

To all whom it may concern:

Be it known that I, DOMINICK W. SHARKEY, a citizen of the United States, residing at Syracuse, in the county of Onondaga and State of New York, have invented a certain new and useful Improvement in Aeroplanes, of which the following is a specification, reference being had therein to the accompanying drawings, forming part thereof.

10 My invention relates to aeroplanes and has for its general object great strength, high speed, reliability, durability and other objects and advantages which will herein-after appear. My present invention relates
15 more particularly to the construction of the wings or planes and the means for mounting them and is a divisional part of the subject-matter of my copending application for patent for aeroplane, filed November 27, 1917, Serial No. 204,156, which became Patent No. 1,315,044, dated September 2, 1919.

1, 1911, dated September 1, 1911.
My invention includes a tube forming the body of the aeroplane and wings forming planes secured to and extending laterally from the sides of such tube, these wings being of a ribbed construction and being detachable from the body-forming tube. My invention also includes, in combination, a frame comprising a plurality of longitudinally extending strength-providing members at the outside of the body-forming wing-supporting tube, and a plurality of strengthening rings tying such frame pieces or members together. My invention further includes features of construction and combinations of parts, as will appear from the following description.

I shall now describe the aeroplane embodying my invention illustrated in the accompanying drawings and shall thereafter point out my invention in claims.

Figure 1 is a top or plan view.

Fig. 2 is an enlarged transverse section on a plane indicated by the line 2-2 of Fig. 45.1 as viewed from the right.

Fig. 3 is a partial section.

Fig. 3 is a partial section similar to Fig. 2 but showing a wing as detached.

Fig. 4 is a front elevation on a reduced scale.

50 Fig. 5 is a side elevation as viewed from below in Fig. 1 and from the left in Fig. 4.

Fig. 6 is a somewhat enlarged central vertical longitudinal section with parts in elevation and other parts omitted.

55 Fig. 7 is a much enlarged vertical longi-

tudinal section of one of the wings on a plane indicated by the line 7-7 of Fig. 1 as viewed from below.

Fig. 8 is a similar view on the line 8-8 to of Fig. 1.

In the aeroplane embodying my invention illustrated in the accompanying drawings, a gradually rearwardly tapered sheet metal tube 1 forms a part of the body frame or fuselage of the machine. A sheet metal hood 2 of substantially semicircular cross-section and shown as slightly tapered in a forward direction extends forward from the upper part of the forward end of the tube 1, forming a forward continuation of the upper part of the tube 1, this semicircular hood 2 forming a part of the wing-supporting framework or fuselage of the machine. The framework or fuselage also includes longitudinal frame pieces 3, shown as four in number, equidistantly transversely circumferentially spaced and tied together at intervals by means of transversely arranged rings 4. All of these frame parts may be of any suitable metal or alloy.

Wings or planes project laterally in opposite directions from the fuselage and are detachably secured to the sides of the body-forming rearwardly tapered tube 1 and to the lower edges of the forwardly extended hood 2. These wings comprise gradually outwardly tapered V-shaped sheet metal ribs 5 which are shown as extending laterally in parallel relation and at right angles to the longitudinal axis of the machine, and in the particular construction illustrated in the drawings, these ribs are shown as seven in number for each wing, and these wing-ribs 5 are all of similar construction, but vary as to their length and cross-section. In the construction illustrated in the drawings the foremost rib 5 is shown as slightly shorter than the next succeeding rib 5, and after this, the ribs 5 are shown as of gradually less length and of correspondingly reduced cross-section so that, as clearly appears in Fig. 1, the wings have the greatest spread near their forward edges and gradually taper on a substantially rounded curve toward the rear. 105

The lower air-engaging wing surface of the wing is shown in the drawings as flat or plane and is formed by a lower metallic sheet 6, which is firmly secured, as, for example, by means of rivets 7 (Figs. 7 and 8) 110

to lateral flanges 8 formed on the wing-ribs 5. At their inner or larger ends the wing-ribs 5 are provided with end flanges 9 which conform to and are firmly secured, for example, by means of rivets 10, to a curved end plate 11. These end plates 11 are curved to conform to the outer surfaces of and are adapted to be detachably secured in place upon the tube 1 and hood 2 of the fuselage or framework of the machine, and are shown as thus secured in place by means of two sets of upper short bolts 12 and by a single set of lower long bolts or tie rods 13 which extend transversely from side to side through the lower edges of the hood 2 and transversely across the tube 1 just below the axis or center line thereof. Simply by removing the outwardly exposed nuts from these bolts 12 and rods 13, the wings may be detached from the body or fuselage, thus providing for convenient transportation and for the easy making of repairs.

The sheet metal plate 6 forming the lower wing surfaces is provided between the wing-ribs 5 with a series of unobstructed openings or apertures 14 of comparatively small diameter, these holes 14 permitting the passage of small quantities of air from the lower to the upper sides of the wings between the ribs 5, so as thereby to prevent the forming of objectionable eddy currents in the air above the wings by the wing-ribs 5.

It will be noted that the wings and entire body structure or fuselage are formed entirely of metal, so that their construction is such as to provide great strength combined with lightness.

The body-forming and wing-carrying tube 1 of the fuselage is also a propulsion tube for driving the aeroplane forward, as is indicated by the propeller 15 appearing in Fig. 6. This part of the aeroplane is the subject of my above mentioned Letters Patent.

The other parts of the aeroplane, some of which appear in the accompanying drawings, and not hereinbefore particularly described, may be of a usual or of any suitable construction. It is to be more particularly noted that lateral balancing control may be effected in substantially a usual way by warping the outer ends or tips of the wings, which are sufficiently flexible for this purpose, and this warping of the wings to obtain the lateral balancing control may be effected in substantially a usual way by means of usual guys 16, shown in Fig. 4. These guys 16 also strengthen the wings in a substantially usual way.

It is obvious that various modifications may be made in the construction shown in the drawings and above particularly de-

scribed within the principle and scope of my invention.

I claim:

1. An aeroplane having, in combination, a longitudinally extending body-forming tube, and wings forming planes projecting laterally from said tube, said wings comprising gradually outwardly tapered ribs secured at their inner ends to the sides of said tube, and an underlying sheet secured to said ribs and forming an air-engaging lower wing surface, the upper portion of the said ribs and the top of the underlying sheet, except where it is covered by the ribs, being exposed to the air.

2. The invention claimed in claim 1 in which the inner ends of said wing ribs are detachably secured to said body-forming wing-supporting tube.

3. An aeroplane having, in combination, a longitudinally extending body-forming tube, and wings forming planes projecting laterally from said tube, said wings comprising gradually outwardly tapered ribs secured at their inner ends to the sides of said tube, an underlying sheet secured to said ribs and forming an air-engaging lower wing surface, all the said parts of said aeroplane being of metal, and curved metal end plates to which the inner ends of the wing-ribs are secured and which are adapted to be detachably secured to said body-forming tube, whereby said wings may be readily removed and replaced.

4. The invention claimed in claim 1 in which the wings have a plural series of unobstructed openings in the wings between the supporting ribs thereof, said openings being of such a size as to prevent the formation of objectionable eddies above the wings.

5. An aeroplane having, in combination, a longitudinally extending body-forming tube, and wings forming planes projecting laterally from said tube, said wings comprising gradually outwardly tapered ribs secured at their inner ends to the sides of said tube, an underlying sheet secured to said ribs and forming an air-engaging lower wing surface, all the said parts of said aeroplane being of metal, and tie rods extending transversely through and across the body-forming tube for supporting the wings.

6. The invention claimed in claim 4 in combination with tie rods extending transversely through and across the body-forming tube and through the lower edges of said end plates for supporting the wings.

7. An aeroplane wing comprising V-shaped sheet metal ribs having their apices upward and gradually tapering from the inner end of the wing toward the tip thereof, and a metallic sheet forming an air-en-

gaging surface firmly secured to the lower sides of said ribs, the upper portion of the said ribs and the top of the underlying sheet, except where it is covered by the ribs, being

5 exposed to the air.

8. An aeroplane wing comprising V-shaped sheet metal ribs arranged in parallel relation one behind the other and gradually tapering in cross-section from the inner end 10 toward the wing tip and arranged with their apices upward, such ribs having lateral flanges and inner end flanges, a metallic

sheet forming a lower air-engaging wing surface firmly secured to said lateral flanges of the ribs, and a metallic supporting sheet 15 firmly secured to said end flanges of the ribs.

9. The invention claimed in claim 7 in which the metallic air-engaging sheet has a plural series of unobstructed openings there-in between the wing-ribs. 20

In testimony whereof, I have affixed my signature to this specification.

DOMINICK W. SHARKEY.
